UNITED STATES PATENT OFFICE.

CHARLES C. PUFFER, OF ROCHESTER, NEW YORK, ASSIGNOR TO THE PFAUDLER COMPANY, OF ROCHESTER, NEW YORK, A CORPORATION OF NEW YORK.

CLOSURE-FITTING.

No. 922,508.

Specification of Letters Patent.

Patented May 25, 1909.

Application filed December 28, 1907. Serial No. 408,434.

To all whom it may concern:

Be it known that I, CHARLES C. PUFFER, of Rochester, in the county of Monroe and State of New York, have invented certain new and useful Improvements in Closure-Fittings; and I do hereby declare the following to be a full, clear, and exact description of the same, reference being had to the accompanying drawings, forming a part of this specification, and to the reference-characters marked thereon.

My present invention relates to closures of the general type employed for instance to control the ports of vessels, inspection or other openings in containers of different kinds and in many kindred ways, and it has for its object to provide a fitting of this nature that may be used to advantage in any of these connections, but which will embody a construction particularly suited to such requirements as are exacted through its use as a closure for the openings in brewing tanks for the purpose of affording a means of obtaining ready access to the interior, or for observing conditions therein. As the internal pressure of these tanks is often considerable, my improvements are directed particularly toward providing a fitting easily attached to the tank and a lid or cover that will be both strong and tight though capable of being unfastened with comparative ease.

To these and other ends the invention consists in certain improvements and combinations of parts all as will be hereinafter more fully described, the novel features being pointed out in the claims at the end of the specification.

In the drawings: Figure 1 is a top plan view of a fitting constructed in accordance with my invention and illustrating one embodiment thereof. Fig. 2 is a central section on the line 2—2 of Fig. 1 showing the manner in which it is secured to the tank.

Similar reference characters in the several figures indicate similar parts.

Tanks of the character indicated are usually constructed of sheet or plate metal and the portions thereof illustrated and indicated by the numeral 1 are adjacent the aperture 2 therein which is of a size suitable for the purposes intended. Inserted in the aperture is a preferably annular frame 3 of substantially the same diameter as the said opening, and provided with a flange 4 en-

gaging upon one side of the plate, a gasket or any suitable packing 5 being inserted between the two. The frame is threaded exteriorly as at 5^a and may be screwed into the tank, if convenient, though this is not altogether necessary as I provide a securing ring or member 6 threaded thereon above the flange to move relatively thereto and engaging the plate 1 upon the opposite side therefrom through the medium of the gasket 6^a or packing member 7. The frame and securing ring are turned relatively to tightly clamp the former within the opening by means of suitable spanner wrenches engaging within the notches 8 and 9 respectively. 70 The portion of the frame projecting exteriorly of the tank is provided with an outwardly extending lug 10 while projecting inwardly from the inner sides of the frame is a shoulder 11 forming a seat for the closure 12. 75 The latter is in the present instance hinged to the frame through a pivotal connection 13 joining a lug 14 thereon with the lug 10 and comprises an annular body portion fitted with a transparent panel 15 held against a shoulder 16 by a ring 17. A downwardly projecting annular flange 18 on the closure narrower than the seat engages and rests upon the latter at its extreme inner edge only, the portions of the body adjacent said 85 flange being reduced and rounded as at 19. The object of this construction is two fold: First, the lugs 10 and 14 remove the pivotal center to a point at which the radius of movement is made greater and the closure approaches the opening in the frame more squarely, and secondly:—The flange bearing only at the edges of the seat exerts its pressure upon a smaller area of a gasket 20 arranged on the latter and compresses it with 95 greater intensity to prevent the escape of gases under pressure.

As a means of fastening the closure in place I employ a plurality of devices fastened to the securing ring 6 and having both a pivotal and rectilinear movement relatively to the closure so that they may be quickly swung into position and then easily tightened into engagement with great mechanical power but a short range of movement. To these ends I provide the closure with a plurality of equidistantly disposed extensions 21 having countersunk sockets 22 therein and open slots 23 leading therefrom. Pivoted at 24 in slots 25 in the securing member 6 are a plu- 110

rality of corresponding and equidistantly arranged bolts 26 adapted to swing within the slots 23 and carrying, threaded thereon, wing nuts 27 having lower faces seating within the 5 sockets 22. It will be seen that the closure may thus be fastened firmly by tightening the nuts into engagement when in the position shown at A, or the latter can be loosened sufficiently to withdraw them from the 10 sockets and the bolts then quickly swing outwardly, as shown at B, and the closure freed for raising. If the fastening devices are equidistantly disposed, as herein described, only a partial rotation of the securing ring is necessary 15 at any time to bring them all into position for register with the portions of the closure to be engaged and the compressibility of the packings 5 and 7 will always permit of this slight movement.

20 I claim as my invention:

1. The combination with a frame having an inwardly extending seat on its inner sides and an outwardly extending lug on its outer side, of a closure hinged to the lug to swing 25 within the frame and having a flange on its under side narrower than the seat and engaging upon the inner edge thereof.

2. The combination with a frame provided with a flange, a securing member arranged 30 above the flange and movable relatively thereto, and a closure fitting within the frame, of a fastening device carried by the securing member and engaging the closure.

3. The combination with a frame provided 35 with a flange, a securing member arranged above the flange and movable relatively thereto and a closure fitting within the frame, of a fastening device carried by the securing member and engaging the closure and 40 having both a pivotal and rectilinear movement relatively thereto.

4. The combination with a frame provided with a flange, a securing member arranged 45 above the flange and movable relatively thereto and a closure fitting within the frame and provided with an open slot, of a bolt piv-

oted to the securing member and movable within the slot in the closure and a nut threaded thereon and engaging the latter.

5. The combination with a frame provided 50 with a flange, a securing member arranged above the flange and movable relatively thereto and a closure fitting within the frame and provided with a socket and an open slot leading therefrom, of a bolt pivoted to the securing member and movable within the slot in the closure and a nut threaded thereon and seating within the socket in this latter.

6. The combination with an annular frame 55 provided with a flange and a securing ring carried thereon above the flange and movable relatively to the latter when rotated, of a closure pivoted to and fitting within the frame and provided with a plurality of open slots and a fastening device carried by the securing ring and movable selectively within the slots.

7. The combination with an annular frame 70 provided with a flange and a securing ring carried thereon above the flange and movable relatively to the latter, when rotated, of a closure pivoted to and fitting within the frame and provided with a plurality of open slots equidistantly placed and a plurality of 75 equidistantly disposed fastening devices carried by the securing ring and movable within the slots.

8. The combination with an annular frame 80 provided with a flange and a securing ring threaded on the frame above the flange, of a closure pivoted to and fitting within the frame and having a plurality of equidistantly disposed sockets on its periphery and open slots leading thereto, a plurality of equidistantly disposed bolts pivoted to the securing 85 ring and movable within the slots in the closure and nuts threaded on the bolts and seating within the sockets.

CHARLES C. PUFFER.
